(57) **CLAIM**

The ornamental design for a bag cover, as shown and described.

DESCRIPTION

FIG. 1 is a perspective front view of a bag cover;
FIG. 2 shows a front view thereof;
FIG. 3 shows a rear view thereof;
FIG. 4 shows a right side view thereof;
FIG. 5 shows a left side view thereof;
FIG. 6 shows a top view thereof;
FIG. 7 shows a bottom view thereof;
FIG. 8 shows a perspective front view of a bag cover in environmental conditions;
FIG. 9 shows another perspective front view of a bag cover in environmental conditions;
FIG. 10 shows a rear perspective of FIG. 9;
FIG. 11 is a perspective front view of a bag cover showing a second embodiment;
FIG. 12 shows a front view of FIG. 11;
FIG. 13 shows a rear view of FIG. 11;
FIG. 14 shows a right side view of FIG. 11;
FIG. 15 shows a left side view of FIG. 11;
FIG. 16 shows a top view of FIG. 11;
FIG. 17 shows a bottom view of FIG. 11;
FIG. 18 shows a perspective front view of a bag cover of FIG. 11 in environmental conditions;
FIG. 19 shows another perspective front view of a bag cover of FIG. 11 in environmental conditions; and,
FIG. 20 shows a rear perspective thereof of FIG. 19.
The broken lines of the figures showing additional portions of a bag cover zipper in FIGS. 1 to 10, a backpack and a bag are included for the purpose of illustrating environmental structure and form no part of the claimed design.

1 Claim, 14 Drawing Sheets
